CLAIM

The ornamental design for a tool box, as shown and described.

DESCRIPTION

FIG. 1 is a front perspective view of my tool box, with the drawers closed, and with a conventional tool box shown in phantom supporting my tool box;

FIG. 2 is a plan view of the tool box;

FIG. 3 is a front elevation view of the tool box;

FIG. 4 is a side elevation view of a first end of the tool box;

FIG. 5 is a bottom view of the tool box;

FIG. 6 is a rear elevation view of the tool box; and,

FIG. 7 is a side elevation view of the opposite end of said tool box.

The phantom lines shown in FIG. 1 are directed to environment and are for illustrative purposes only, forming no part of the claimed design.
